No. 777,519.

PATENTED DEC. 13, 1904.

W. A. LEE.
DISK BEARING.
APPLICATION FILED JULY 17, 1903.

NO MODEL.

UNITED STATES PATENT OFFICE.

WILLIAM A. LEE, OF BLACKWELL, OKLAHOMA TERRITORY.

DISK-BEARING.

SPECIFICATION forming part of Letters Patent No. 777,519, dated December 13, 1904.

Application filed July 17, 1903. Serial No. 166,023. (No model.)

To all whom it may concern:
 Be it known that I, WILLIAM A. LEE, a resident of Blackwell, in the county of Kay and Territory of Oklahoma, have invented certain new and useful Improvements in Disk-Bearings; and I do hereby declare the following to be a full, clear, and exact description of the invention, such as will enable others skilled in the art to which it appertains to make and use the same.

My invention relates to an improved disk-bearing, the object of the invention being to provide an improved journal-bearing adapted to support a disk at each end and which will be self-lubricating and dust-proof and capable of various adjustments to locate the disks in any position desired; and with this object in view the invention consists in certain novel features of construction and combinations and arrangements of parts, as will be more fully herein-after described, and pointed out in the claims.

In the accompanying drawings, Figure 1 is a view in vertical longitudinal section, illustrating my improvements. Fig. 2 is a view in section, taken at right angles to Fig. 1. Figs. 3, 4, and 5 are views illustrating the parts detached, and Fig. 6 is a view illustrating a modification.

1 represent bars secured to and carried by any desired form of frame, and to the forward end of said bars my improved journal-bearing box is secured, as will now be described. The bars 1 are secured to the opposite sides of an upright web 2 on a plate or casting 3, which latter is secured upon a flat extension 4 on journal-bearing box 5, and said plate 3 and extension 4 are made with elongated slots 6 for the passage of bolts 7 to secure them together, but permit of adjustment to locate the box at any angle desired.

The journal-box 5 has integral sand-bands 8 at both ends and is adapted to receive a hollow cylindrical journal 9, which projects at both ends beyond the box and is externally and internally screw-threaded at both ends, as shown. On the external screw-threads at both ends collars 10 are screwed and located and are made with annular grooves to receive

the sand-bands 8 and exclude all dirt and grit from the bearing. The furrow-opening disks 11 are located on the journals against collars 10, and headed screws 12 are screwed into the ends of journal 9, closing the same and effectually clamping the disks 11 between the heads of screws 12 and collars 10. Openings are provided in the journal 9 and box 5, through which lubricant can be supplied to the journal and fed thereby to the bearing, and, if desired, the journal can be filled with waste to more effectually hold and feed the lubricant.

In Fig. 6 I show a modified construction of my improvements in which I dispense with the internal screw-threads at the ends of the journal and extend the latter through the disks, screwing cap-nuts 13 onto the ends of the journal and clamping the disks between the nuts and collars 10.

Various other slight changes might be made in the general form and arrangement of the parts described without departing from my invention, and hence I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. In a disk-bearing, the combination with a hollow journal having lubricant-holes, of a journal-box shorter than said journal and having a lubricant-hole, screws entering the respective ends of said journal, and collars secured to the ends of the journal-box, said collars and screws serving as clamping means for disks.

2. In a disk-bearing, the combination with a journal having external and internal threads at both ends, of a journal-box shorter than the journal, screws entering the ends of the journal, and collars screwed on the ends of the journal beyond the ends of the journal-box, said collars and screws serving as means for clamping disks to the journal.

3. In a disk-bearing, the combination with a journal having external and internal threads

at both ends, of a journal-box shorter than the journal, collars screwed on the ends of the journal beyond the ends of the journal-box and having grooves to receive the ends of said journal-box, and headed screws entering the ends of the journal for clamping disks against the outer faces of said collars.

In testimony whereof I have signed this specification in the presence of two subscribing witnesses.

WILLIAM A. LEE.
